UNITED STATES PATENT OFFICE.

CHARLES S. BEEBE, OF RACINE, WISCONSIN.

TWO-WHEELED VEHICLE.

SPECIFICATION forming part of Letters Patent No. 323,257, dated July 28, 1885.

Application filed November 12, 1884. (No model.)

To all whom it may concern:

Be it known that I, CHARLES S. BEEBE, of Racine, in the county of Racine, and in the State of Wisconsin, have invented certain new 5 and useful Improvements in Road-Carts; and

I do hereby declare that the following is a full, clear, and exact description thereof.

My invention is an improvement on a road-cart for which Letters Patent No. 292,277 10 were granted to me January 22, 1884; and its object is to prevent jarring from the motion of the cart-body, as will be more fully described hereinafter.

The drawing represents an under side plan 15 view of a cart-body fitted with my improved device.

A is the cart-body; B, the side bars; C, the springs; D, the shafts, and D' the axle. The side bars, B, are connected about their center 20 by a transverse rod, E, and at their rear end by a similar rod, F. These rods E F are each supported by swinging arms E' F', straddling the side bars at points corresponding with their position in reference to the rods E F. 25 The body A rests on these rods, being secured in place thereon by means of the staples g g', fastened in the under side of the body.

As described in the specification forming part of the Letters Patent above mentioned, 30 rubber washers G may be interposed between the arms E' F' and the body of the cart to prevent jarring caused on uneven roads by the side motion of the said body; but I prefer to use in connection with these washers or 35 without them the coil-springs H, and these

are mounted on the rod E, as shown, with their outer ends abutting against the inner edges of the staples g g', and their inner ends being held in position by the pins h h passing through the said rod.

Instead of the coil-springs H, I may use other forms of springs suitably fastened to the body of the cart and to the arms, so as to work in substantially the same manner. I may also vary the mode of mounting the same without 45 departing from the spirit of my invention.

Having thus described my invention, what I claim as new, and desire to secure by Letters Patent, is—

1. In a road-cart having its body supported 50 on transverse rods depending from swinging arms of the side bars, coil-springs mounted on the supporting-rods between the staples connecting the same to the body of the cart and stop-pins of the rods, substantially as and for 55 the purpose set forth.

2. In a road-cart, in combination with the body A, side bars, B, having swinging arms E' F', rods E F, staples g g', and pins h h, the rubber washers G G, and coil-springs H H, 60 substantially as shown and described, and for the purpose set forth.

In testimony that I claim the foregoing I have hereunto set my hand, at Racine, in the county of Racine and State of Wisconsin, in 65 the presence of two witnesses.

CHAS. S. BEEBE.
